UNITED STATES PATENT OFFICE.

JOHN SANDERS, OF DENVER, COLORADO.

PLOWSHARE WITH REMOVABLE POINT.

Application filed May 28, 1923. Serial No. 641,909.

To all whom it may concern:

Be it known that I, JOHN SANDERS, a citizen of the United States, residing at Denver, in the city and county of Denver and

5 State of Colorado, have invented certain new and useful Improvements in Plowshares with Removable Points; and I do declare the following to be a full, clear, and exact description of the invention, such as will enable others skilled in the art to which it appertains to make and use the same, reference being had to the accompanying drawings, and to the characters of reference marked thereon, which form a part of this

10 15 specification.

This invention relates to improvements in plowshares.

It is well understood by those versed in the art of agriculture that plowshares are subject to rapid wear and that they have frequently got to be removed for the purpose of sharpening the point and edges thereof. The part known as the "point" of the share is subject to the greatest wear and 20 25 is often broken and bent, owing to the presence of rock in the land.

It is the object of this invention to produce a plowshare that shall be so constructed that the point thereof can be readily removed, when worn or damaged, and replaced by a new or different point.

I am aware that removable or replaceable plow points have been made and I am therefore not claiming to be the first one to have invented this combination in its broadest aspect, but I have invented a new and improved plowshare in which the point is applied and removed in a different manner than that employed in connection with any 30 35 40 similar devices known to me, my invention therefore being in the nature of an improvement.

In order to better and more clearly describe my invention, I shall have reference to the accompanying drawing in which the preferred form thereof is shown, and in which:

Fig. 1 is a top plan view of my improved plowshare;

50 Fig. 2 is a bottom plan view taken looking in a direction perpendicular to the share side;

Fig. 3 is a section taken on line 3—3, Fig. 1;

55 Fig. 4 is a top plan view of the front

end of my improved plowshare, the point thereof being removed; and

Fig. 5 is a view looking in the direction of the arrow 5 in Fig. 2.

The same reference characters will be used 60 to designate the same parts throughout the several views.

Numeral 1 designates my plowshare as a whole and 2 designates the removable point. The plowshare comprises a share 65 side 3 which has a cutting edge 4 and a landside 5 which has a removable plate 6 secured thereto by rivets or bolts 7. This plate can be replaced when worn. Plate 6 terminates short of or to the rear of the 70 point 8 of the share and has a forwardly projecting portion 9 whose function will hereinafter appear. The share side of the plowshare is offset on line 10 near the point thereof. The extent of this offset is equal 75 to the thickness of the material of the point. An opening 11 is provided in the share at the offset. Directly over the opening a tongue 12 projects forwardly a short distance. Near the point of the share there 80 is a keyhole-shaped opening 13 with the enlarged circular part to the front thereof. The point 2 has a share portion 14 and a landside portion 15 which has at its rear end a notch for the reception of the projecting part 9. The share portion 14 is provided at its rear end with a tongue or finger 16 which is slightly curved and offset in the manner shown in Fig. 3. The finger 16 is adapted to be inserted through or into the 85 opening 11 (Fig. 3). A rivet 17 projects through the share portion 14 and extends below the same a short distance. The lower end of the rivet is provided with a rounded head 18 which is of such a diameter that it 90 will freely pass through the enlarged portion of the keyhole slot, the narrower portion of which is of a width equal to the diameter of the bolt. The relationship of the rivet, the keyhole-shaped opening 13, the 100 rivet 17 and the finger 16 is such that after the finger 16 has been inserted in the hole 11 a short distance, the head 18 of the rivet 17 can be inserted into the opening 13, after which the point 2 is slid rearwardly as far 105 as it will go. As the point is moved rearwardly the rivet 17 will slide into the narrow slot portion of the keyhole opening 13, and when the parts are in operative position, the lower surface of finger 16 will act as 110

a lock as it engages the front edge of the opening 11. As the point 2 is never subjected to any strain, tending to move it forwardly, but almost exclusively to a force, 5 tending to move it rearwardly, it will be securely held in place.

In order to enable the point 2 to be readily removed, I provide an opening 19 in the part 3 a short distance to the front of the 10 opening 11 and an opening 20 in the part 14. The opening 20 is slightly to the rear of the opening 19 when the parts are in their assembled position (Fig. 3). When the point is to be removed, a rod or bolt 15 21 is inserted through holes 19 and 20 and used as a lever for moving the point forwardly against the locking action of the finger 16. The underside of the share 3 is cut away at 22 so as to provide a space 20 for the finger 16.

It will be seen from the above description that with a plowshare constructed in accordance with my invention, the point can readily be applied and removed and that the 25 plowshare will not have any parts thereof of undue thickness after the point is in place. Where the points are secured to the share without first offsetting the same, the point will be exceedingly clumsy and will not scour 30 properly. With my construction, the share will have a smooth upper surface and the landside will also present a plane surface. The point can be applied and removed without the use of wrenches and other tools, the 35 only tool necessary being the rod 21 and a hammer. I want to call particular attention to the means employed for holding the point in place,—the tongue 16, which serves as a lock, the rivet 17, which engages with the 40 keyhole-shaped opening 13, and the projection 9, all of which means I verily believe to be new in this particular combination.

Having now described my invention, what I claim as new is:

45 1. A plowshare having the front end of the shareside thereof offset, the landside of the share having a removable plate secured thereto, the shareside having an opening at the offset, and a keyhole-shaped opening between the first named opening and the front 50 end of the plowshare, a removable point having a share portion, a landside portion, a finger adapted to cooperate with the first named opening and a rivet adapted to co- 55 operate with the keyhole-shaped opening for holding the point in place in the share.

2. A plowshare having the front end of the shareside thereof offset, the landside of the share having a removable plate secured thereto, the shareside having an opening at the offset, and a keyhole-shaped opening between the first named opening and the front end of the plowshare, a removable point having a share portion, a landside portion, a finger adapted to cooperate with the first named opening, a rivet adapted to cooperate with the keyhole-shaped opening for holding the point in place in the share, and interlocking means between the landside portion of the plowshare and the point. 70

3. A plowshare having the front end of the shareside thereof offset, the landside of the share having a removable plate secured thereto, the shareside having an opening at the offset, the rear side of said opening having a forwardly extending portion, a keyhole-shaped opening in front of said last named opening, a removable landside portion secured to the plowshare, a removable point provided with a tongue adapted to engage with the first named opening, a rivet adapted to cooperate with the keyhole-shaped opening, a landside portion adapted to supplement the portion on the plowshare, interlocking means on said landside portion, and means on the finger for engaging the forward edge of the first named opening to hold the point in place. 75

4. A plowshare having the front end of the shareside thereof offset, the landside of the share having a removable plate secured thereto, the shareside having an opening at the offset, the rear side of said opening having a forwardly extending portion, a keyhole-shaped opening in front of said last named opening, a removable landside portion secured to the plowshare, a removable point provided with a tongue adapted to engage with the first named opening, a rivet adapted to cooperate with the keyhole-shaped opening, a landside portion adapted to supplement the portion on the plowshare, interlocking means on said landside portion, and means on the finger for engaging the forward edge of the first named opening to hold the point in place, said plowshare and point having holes that are eccentric in their normal position and adapted to receive a tool, whereby the point may be moved relative to the share. 90

In testimony whereof I affix my signature.
JOHN SANDERS.
